UNITED STATES PATENT OFFICE.

ROY E. THOMPSON, OF NEW YORK, N. Y., ASSIGNOR, BY MESNE ASSIGNMENTS, OF ONE-HALF TO ALFRED VICTOR BEER, OF NEW ORLEANS, LOUISIANA.

RAILWAY BLOCK SYSTEM.

1,135,225.

Specification of Letters Patent.

Patented Apr. 13, 1915.

Application filed February 7, 1912. Serial No. 675,968.

To all whom it may concern:

Be it known that I, ROY E. THOMPSON, a citizen of the United States, and resident of New York city, borough of Manhattan, in the county of New York and State of New York, have invented certain new and useful Improvements in Railway Block Systems, of which the following is a specification.

My invention has reference to improvements in block signaling systems for railroads, and is particularly adapted to control the operation of signaling, train stopping or analogous devices located on an engine or the like.

My invention comprises novel details of improvement and combinations of parts that will be more fully hereinafter set forth and then pointed out in the claims.

Reference is to be had to the accompanying drawings forming part hereof, wherein,

Figure 1 is a diagrammatic view illustrating my improvements applied to a railway track in which the traffic is intended to be in one direction only, as to the east; Fig. 2 is a similar view in which the traffic is intended to be only in an opposite direction to Fig. 1, as to the west; Fig. 3 is a diagrammatic view illustrating a portion of Fig. 2, together with devices to be applied

in the cab of an engine or the like for signaling or train stopping; Fig. 4 illustrates a practical form of the interrupter 70, which may be in the form of a well known buzzer; Fig. 5 is a view similar to Fig. 2 illustrating additional devices, whereby both a signal and a train stopping device upon the engine may be controlled; Fig. 6 is a view substantially similar to Fig. 5 illustrating the adaptability of the device

to a track whose traffic is in the direction opposite to that shown in Fig. 5; Fig. 7 is a diagrammatic view illustrating the adaptability of my invention to a single track railway in which the traffic is intended to be in opposite directions, wherein a signal or train stopping device on an engine may be operated, by reason of danger ahead with respect to such train, in accordance with its direction of travel; Fig. 8 is a diagrammatic view illustrating the wiring for a siding in connection with my invention; Fig. 9 is a diagrammatic view illustrating the adaptability of the invention illustrated in Fig. 7 to a single track rail-

way crossing; Fig. 10 is an enlarged diagrammatic view of a portion of the devices illustrated in Fig. 7, illustrating further the relation of the signaling or train stopping devices in connection therewith; Fig. 11 is a detail view of a practical form of the polarized interrupter 50, 51, etc.; Fig. 11^a is a diagrammatic illustration of a modified form of the polarized interrupter of Fig. 11; Fig. 12 is a plan view of Fig. 11, parts being removed; Fig. 13 is an enlarged detail of the contact devices of the interrupter of Figs. 10, 11 and 12; Fig. 14 is a detail of the armature 45; Fig. 15 is a diagrammatic view illustrating the adaptation of my invention to a single track railway, as in Fig. 7, embracing means for controlling signals as well as train stopping devices on an engine; Fig. 16 is a diagrammatic view illustrating shoes for controlling pole changers or interrupters where the third rail for the shoes may be on one or both sides of the track, or may be alternated on opposite sides of the track, and Fig. 17 is a diagrammatic view illustrating an arrangement for controlling the pole changers or interrupters irrespective of the position of the engine upon the rails in either direction of its travel.

Since I have illustrated various track and third rail blocks in the accompanying drawings, in conjunction with which blocks corresponding devices are associated, I have, for convenience, lettered corresponding numerals of reference with corresponding letter priming, from which it will be understood that a numeral and a corresponding numeral with an added letter refer to a similar part in the various blocks.

Referring to Figs. 1 to 6, in which the arrangements are intended for traffic upon a track in one direction only, the track is illustrated as divided into blocks 12, 12^a, 12^b etc. each insulated from the other, and a third rail also divided into corresponding blocks 11, 11^a, 11^b etc., each insulated from the other, with each of which blocks signal or train stopping devices are associated, whereby such devices will be set one or more blocks behind a train, to cause operation on the engine of a train approaching from the rear of the signaling devices on the last named engine. Normally, when there is no engine or other form of danger on the track, as in

Fig. 1, the track batteries 10, 10^a, etc. cause the track relays 14, 14^a, etc. through the wiring 13, 13^a, 15, 15^a, etc. to attract their corresponding armatures to normally close the circuits at 31, 31^a of third rail blocks 11, 11^a, etc. I thus attain with one battery the double effect of maintaining closed track battery circuit (for an engine) in one block and a partially closed third rail circuit in the block immediately to the rear, which will be utilized by the battery on an engine when the engine comes into such third rail block to cause its signaling or train stopping devices not to operate, thereby giving a clear signal.

In Fig. 3 devices are represented as adapted to be placed upon an engine for controlling safety devices on the engine, and the engine in addition carries the battery 110 which is normally in circuit with the engine wheels 119 and the third rail shoe or brush 100 carried by the engine. Normally when an engine comes into a block (such as block 12 in Fig. 3), the engine battery 110 gets a circuit as follows: from battery 110, through primary winding 118 of the induction coil or transformer 120, thence through shoe 100, third rail 20, wire 40, armature contact 31, armature 71, interrupter 70, wire 55 to track, thence to the wheels of the engine 119 to battery 110, causing a safety signal to be held clear, or a train stopping device to be held inoperative on the engine. The signaling device or train stopping device represented at 140, 141 in Fig. 3, which will be termed safety devices, and may be in any well known form, are operated by means of the circuit last described on assumption that battery 110 continues to flow through the last named circuit, and is interrupted therein as long as the train is in this block, and while there is no danger ahead of a train. The solenoid 130, which is normally energized maintains the safety devices 140 normally at safety or a corresponding train stopping device inoperative, as it is normally energized by battery 131, the circuit of which, including wire 135, is controlled by a circuit breaker 122 included in the circuit of the secondary 121 of induction coil 120. Thus, when the circuit from battery 110 through 118, 70 etc., previously described, is closed, the pulsation caused by the interrupter 70, 71, induce current in secondary 121 causing circuit breaker 122 to close the circuit at 132 of local battery 131, and thus maintain solenoid 130 energized. It will be understood that track relay 14 associated with the block ahead of block 12 (Fig. 2) will, under the operations above set forth, be energized by reason of the circuit of its track battery being closed, and will therefore have maintained the circuit closed at 31. If, however, through any cause whatever, the circuit of the track battery in the

block ahead of block 12 had been broken or short circuited, as by a train being in such block, the track relay 14 would be deenergized, its armature would have moved back and broken the circuit at 31, hence the interrupter 70 would not operate and the secondary 121 in the engine in block 12 would be deenergized. The core 134 of circuit breaker 122 would move back, being pulled by spring 138 in the illustration in Fig. 3, thereby breaking the circuit of battery 131 at 132, thereby deenergizing solenoid 130 and causing the safety device 140 to be set by the dropping of its weight 141. The break at 132 in the circuit of battery 131 occurs when spring 132 meets stop A, as core 134 will be pulled back until it meets stop 139. The safety device will operate until the danger ahead disappears, or if the engineer wishes to proceed farther in the block, he may move switch 136 to contact 137 thereby closing the local circuit of battery 131, and thus restoring the safety device to normal. When circuit breaker 122 is again energized, by reason of the danger ahead disappearing, core 134 first comes in contact with spring 132, re-establishing the normal circuit through the core of the circuit breaker through spring 132 for battery 131, and when the core comes to rest it will have moved switch 136 away from contact 137 by having caused contact 132 to have shifted switch 136 from contact 137, and the normal circuit of battery 131 through circuit breaker 122 will then remain established.

From the foregoing it will be understood that the safety device 140 will be operated in an engine when it is in a block next behind the block containing danger, such as a train. In addition to this, it may be desirable to cause safety device 140 to operate in the second block behind the block containing danger when such safety device is in the form of a signal, and to cause train stopping devices to be operated in an engine when it is in a block next behind a block containing danger, so that the engineer would, if he passed through a block causing operation of his safety signal, and passed into a block adapted to operate the train stopping devices of his engine, be stopped before proceeding into the block containing danger. To this end I utilize the devices described with respect to Figs. 1 to 4, and in addition thereto circuits controlled by said devices to operate the safety device 140 as a signal and train stopping device 162 in blocks two removed and one removed respectively behind danger, as illustrated in Figs. 5 and 6. Referring to Fig. 5, a train is illustrated at 119 in block 12 and a train 119^a in block 12^a, two blocks to the rear of train 119, and it will now be shown that the signal device 140 of train 119^a will be affected by reason of train 119 being in block 130.

12, and that if train 119^a should proceed into block 12^a while train 119 remains in block 12, the train stopping device 162 of train 119^a will be operated. It has been shown that the safety device 140 will operate one block behind danger when the interruptions in the circuit of battery 110 cease by reason of the break in the circuit at 31. It also will be understood that such interruptions will cease if the current from battery 110 finds a path, such as a short circuit, around interrupter 70. The same effect takes place in the arrangement shown in Figs. 5 and 6 in the block behind that containing danger, and in addition thereto means are provided for causing the operation of safety device 140 in the block second behind danger. These actions are effected as follows, with reference to Figs. 5 and 6: with train 119 in block 12 (Fig. 5) its wheels will short circuit battery 10 causing track relay 14^a to become deenergized, breaking circuit at 31^a and establishing another circuit at 183^a, the latter serving to control safety device 140 of train 119^a in block 12^b. To this end the following is provided: Considering the effect of battery 110^a traced from the positive side the following will result: from battery through primary 118, circuit breaker 115, thence to shoe 100^a, third rail 20, wire 40^b, contact 31^b, thence through armature to vibrating member 71^b, thence through the normally closed contact at 128^b to armature 187^b, 70^b to 180^b, thence by wire 55^b to the track in block 12^b, thence through the wheels of engine 119^a back to the negative side of the battery. It will be seen that the first effect of the closing of this circuit has sufficient impulse in interrupter magnet 70^b to attract vibrator 71^b and break the circuit thereat, whereupon the current will now flow through the shunt 185^b, 183^b, 181^b, 180^b, causing the armature 187^b of 181^b to break the first named circuit at 188^b and the circuit for battery 110^a will now be as follows: tracing the battery circuit from the positive side as before to the point 185^b the circuit will now continue through the line wire to contact at 183^a (which was previously established by the deenergizing of track relay 14^a as before described), thence through the line to relay 181^b to point 180^b, thence to track in block 12^b to the wheels of engine 119^a back to the battery. It will be seen that so long as the circuit is closed at 183^a relay 181^b will maintain the circuit of 71^b and 70^b broken at 188^b, with the result that the current from battery 110^a will not be interrupted by interrupter 70^b, but will flow continuously, keeping the circuit breaker 115 energized, but deenergizing the circuit breaker 122, as it is well known that only a pulsating or alternating current will induce current from the primary 118 to the secondary 121. Thus, the safety device 140 will be set to danger in engine 119^a in block 112. At the same time the fact of breaking the circuit at 188^b and establishing the circuit through relay 181^b and 183^a as before described, has the effect of causing circuit breaker 115 to remain energized, it being understood that circuit breaker 115 is normally energized when its engine is not in a block adjacent danger. It will be understood that circuit breaker 115 is operative either upon a pulsating or direct current. Hence when train 119^a entered block 112^b circuit breaker 115 remained energized until train 119^a enters block 12^a. Circuit breaker 115 remaining energized will keep solenoid 150 energized through the closing of its circuit to prevent the operation of the train stopping device 162 while the train remains in block 12^b. If train 119^a proceeds into block 12^a the circuit breaker 115 will become deenergized, as it will be seen that battery 110^a of train 119^a finds an open circuit in block 12^a by reason of the circuit having been opened at 31^a as before described, because train 119 is in block 12, and deenergized relay 14^a. Hence, the local circuit through battery 131 of solenoid 150 will be broken at 152 by the dropping of the core of circuit breaker 115, causing spring 151 to move away from contact 152. The deenergizing of solenoid 150, now taking place, causes its core 160 to be released, permitting the weight 164 to drop and throw the train stopping devices 162 to the operative position, turning at the pivots 163 and 161. Should the engineer wish to proceed in block 12^a he may do so by throwing switch 136 to contact 137 to close the local circuit of battery 131 through solenoid 150 causing it to reestablish the normal condition for running the train either by turning on steam or an electric circuit and letting off the brakes or otherwise, as such devices may be organized in any well known manner. It will be understood that when the danger is removed ahead of the train that has been signaled or stopped, the corresponding track relays etc. will re-assume their normal positions and the safety devices and train stopping devices will also be restored to their normal or other positions according to the character of the blocks still ahead, due to the restoration of the circuits or the reestablishment of the normal battery flow through the various instruments affected by the same.

With reference to Figs. 7 to 15, illustrating my improvements applied in a single track railway system, where the traffic is intended to be in opposite directions upon the same track, reference will first be made to Figs. 7 to 14 illustrating a simple form of device, and having the effect of setting a safety device, which may be in the form of a signal or train stopping device, or the like, on the engine. Certain of the parts before described, having been numbered, in Figs. 130

7 to 14, correspondingly to those in Figs. 1 to 6, operate in the manner before described, and in addition to such parts means are shown for causing operation of the safety device of a train approaching a source of danger from either direction on the same track. In this case the shoe 100 carried by an engine is set to always trail or lag in a rearward direction with respect to the movement of the engine, and will cause positive or negative current to be sent over third-rail 20, according to the installation of the system with respect to the direction of travel as from east to west and vice versa. In Fig. 15 the arrangement illustrated is such that it is intended for positive current to always be sent to third-rail 20 when a train is moving from right to left of the drawing, and negative current sent to third-rail when the train 20 is moving from left to right. To accomplish the desired effects from such arrangement of current flow, I have illustrated a special form of polarized interrupter adapted to operate in controlling signals with either negative or positive current, the arrangement 25 also being such that a source of danger, such as a train, in a block, will cause one of the interrupter magnets, as to the west of such train, to be affected for controlling the safety device of a train approaching from the west, and at the same time will affect one 30 of the magnets of an interrupter to the east of said train in the block, affecting the safety device of a train approaching from the east. 35 To this end the polarized interrupters are indicated at 50, 51, 50^a, 51^a etc., and for purpose of description I will term the interrupter coils 50, 50^a etc. the easterly coils, and the coils 51, 51^a etc. the westerly coils, since 40 the coils 50, 50^a etc. control safety devices of trains going toward the east in the example under consideration, and the coils 51, 51^a control trains going toward the west, and such coils have no effect upon safety devices 45 of trains going in a direction reverse to that mentioned with respect to such coils. In Figs. 7 to 14 I have illustrated the safety device 140 which may be either a danger signal or a train stopping device as before described.

The track wiring is more fully illustrated in Fig. 7, and the engine wiring and its relation to the track wiring are more fully illustrated in detail in Fig. 10. Assuming 55 that a train going in a westerly direction causes positive current to be sent to the third-rail 20 (as will be explained with respect to Fig. 10), it will now be explained how such current will be controlled in such 60 a manner as to stop the normal interruptions in the circuit of such current when said train is in a block adjacent to a block containing danger, to the westward of said train, and it will be further shown that if a 65 source of danger exists in the adjacent block

next easterly to said train, a portion of the interrupter associated with the block containing such train will be affected, but not in such a manner as to stop or control such train by reason of danger in such easterly 70 block. Taking as an example in Fig. 7 train 119^b and its rear portion 119^c (the train being illustrated in blocks 12^c and 12^d) the following effects will be produced, viz: referring more particularly to interrupter 50^c, 75 51^c associated with block 12^c (the description of which interrupter will apply to other corresponding interrupters illustrated), the coil 50^c will act to attract the permanent north pole armature 45^c only when positive 80 current is sent to track, while the coil 51^c will only attract the north pole armature 45^c when positive current is sent to third-rail from the engine battery 110^b. Assuming engine 119^b in block 12^c sets the corresponding 85 device to control an approaching train in block 12^b, the wheels of train 119^b occupying block 12^b, by virtue of short circuiting the track battery 10^c, will cause the track relay 14^c to release its armature, breaking 90 the line circuit at 31^c, containing battery 30^c, without affecting the interrupters 50^c, 51^c of block 12^c. The breaking of this circuit will cause the line relay 33^c of block 12^b to the west and the line relay 35^c of block 12^d to 95 the east to drop their armatures.

With respect to block 12^b the following conditions are thus established with relation to a train such as 119^a traveling toward the east, and located in block 12^a; with respect 100 to its entry into block 12^b, viz: as has been stated, trains traveling to the east will furnish negative current to the third rail 20, hence while train 119^a is in block 12^a there is no effect upon the devices of block 12^b; 105 should the train 119^a pass from block 12^a into block 12^b, then such train will be affected in the following manner: Starting from the positive side of the battery 110^a current will flow through the engine wheels 110 to the track in block 12^b, thence through the wire 15^b, point 55^b to the point 54^b. As the contact 53^b is open, none of the current can 110 pass over the easterly coil 50^b, and therefore the entire current will be compelled to pass 115 through the armature 38^b and the contact 52^b (assuming that the contact 52^b will now be closed owing to said train 119^a having passed out of block 12^a from which the relay 35^a is controlled), thence through the westerly coil 120 51^b, wire 49^b to point 47^b, wire 46^b, spring contact 44^b, stationary contact 41^b, spring contact 42^b, wire 40^b, third-rail 20 (of block 11^b), shoe 100^a and back to negative side of battery 110^a. Owing to the direction that 125 this current is made to take through the winding of the coil 51^b of the interrupter, such coil is made a north pole, and it will be understood that there will be no attraction between the coil 51^b and the north pole 130

armature 45^b. Therefore the armature 45^b will not assume a position against the spring contact 42^b, but on the other hand will be repelled with decreasing force until it comes to rest against spring contact 44^b. This force, however, will not be sufficient to overcome the spring 44^b, and it will remain against the permanent contact 41^b, permitting the current to flow uninterruptedly, and as it has heretofore been shown, an uninterrupted current will not induce a current in the secondary 121 (Fig. 10), the circuit breaker 122, will drop its core and the safety device 140 will operate, and the train 119^a 10 will receive a danger signal or be stopped, as desired. It will be understood, as hereinbefore described, that interruptions have been taking place in the circuit of primary coil 118^a until train 119^a has entered block 12^b, and such interruptions cease for the reasons last described. In this case the pulsations in the circuit of coil 118^a have been maintained, while train 119^a was not in block 12^b, but was in a block to the west of block 12^b, as in block 12^a, as follows: Assuming train 119^a to occupy the position shown in block 12^a (Fig. 7) the circuit of battery 110^a will be interrupted in the following manner: Current from positive side of battery 110^a 20 will flow to wheels, track, wire 15^a, point 55^a to point 54^a. Contact 52^a being open due to the effect of train 119 on line relay 35, and said line relay releases its armature 38^a, the entire current will flow through the armature 39^b, through 53^a, and through the easterly coil 50^a, wire 48^a to point 47^a, wire 46^a, spring contact 44^a, stationary contact 41^a, spring contact 42^a, wire 40^a, third-rail 20, of third-rail block 11^a, shoe 100^a and to negative of battery 110^a. However, the current will pass through the winding of the easterly coil 50^a in such a direction as will make it a south pole. Therefore, the permanent north pole armature 45^a will be attracted with sufficient force to break the circuit between 44^a and 41^a, and alternate makes and breaks in the circuit will be maintained owing to the spring 44 restoring itself against contact 41^a when the coil 50^a becomes deenergized, and so on producing rapid pulsations in the circuit of battery 110^a containing the primary winding 118^a of the corresponding induction coil. Such conditions continue in the easterly coils as the train 50 proceeds to the east until interrupted by entering a block in which an easterly coil circuit has been opened by reason of a train or danger in an adjacent block as before described. It having been stated above that armature 38^a was released from contact 52^a by reason of line 35 being deenergized because of the presence of train 119 in block 12, for which reason all the current from battery 110^a was compelled to flow as before described through coil 50^a, it will be under- 60 stood that if there was no danger or train in block 12 relay 35 would remain energized by reason of the closed circuit at 31 of line battery 30, hence the current for the interrupter 50^a, 51^a in block 12^a, would be caused to flow through both coils 50^a, 51^a, with the following effect: The current from battery 110^a would then divide equally at the point 54^a, one-half flowing through the winding of coil 50^a with the same effect as heretofore described, the other half flowing through the armature 38^a, contact 52^a, winding of westerly coil 51^a, wire 49^a, and reuniting with the other half at the point 47^a, the full current thence continuing through 46^a back to battery 110^a as before described. The result of one-half of the current being diverted through coil 51^a would be to make the coil 51^a a north pole owing to the direction in which said current is made to flow through such coil, thus causing coil 51^a to repel the north pole armature 45^a thereby helping the coil 50^a in producing the vibrations of such armature. If a train or danger should come into block 12 thereby causing the deenergizing of line relay 35, and the consequent breaking of the last named circuit of winding 51^a at 52^a the full current from 54^a will flow through 50^a with the result previously described. 70 80 85 90 95 100 105 110 115 120 125 130

It will now be shown what effect the train 119^a while in block 12^a has upon a train approaching into block 12^b, from the east as well as a train approaching into block 12 from the west. Assuming that train 119^b passes into block 12^b, while train 119^a is in block 12^a, train 119^a will find the following conditions with respect to its safety device, viz: the wheels of train 119^a having short circuited battery 10^a causing track relay 14^a to drop its armature and break the circuit at 31^a containing battery 30^a, thereby causing line relay 35^a to release its armature 38^a from contact 52^b of block 12^b, and at the same time causing line relay 33^a to release its armature 39^a from contact 53 of block 12, it will be seen that it has opened a circuit through the easterly interrupter coil 50 of block 12, and the westerly interrupter coil 51^b of block 12^b. Interruptions in the circuit of primary 118^b of the induction coil of train 119^b, because it is proceeding to the west, will be caused to cease to effect the operation of safety device 140 of train 119^b as follows: Assuming that train 119^b with its rear 119^b has passed fully into the block 12^b, line relay 33^c would again become energized through the closing of the contact 31^c of the circuit containing line battery 30^c, because of track relay 14^c having again become energized through its battery 10^c, and said line relay 33^c would restore its armature 39^c against contact 53^b, establishing a circuit for the engine battery 110^c, through the easterly coil 50^b. However, the circuit 130

through the westerly coil 51^b will remain open at 52^b due to the presence of train 119^a in block 12^a, and although the current from battery 110^b will be directed to flow through the easterly coil 50^b, no attraction will be produced on north pole armature 45^b owing to this current flowing through 50^b in such a direction as to make it a north pole, in a manner heretofore described with respect to battery 110^a. Hence no interruptions will take place between the spring 44^b and the stationary contact 41^b with the result in the coil 118^b that there will be no current induced in the secondary thereof, thus causing a corresponding local circuit of its battery corresponding to 131 (Fig. 10) to open, thereby causing the operation of safety device 140 of train 119^b. When train 119^b first enters block 12^b, approaching train 119^a in block 12^a, it will affect safety device (140) in train 119^a in a manner similar to the described effect on the safety device of train 119^b by reason of the presence of train 119^a in block 12^a. This may be described as follows: The first effect of train 119^b in block 12^b will be to short circuit the battery 10^b, and thereby cause track relay 14^b to release its armature breaking circuit at 31^b containing the battery 30^b, thereby deenergizing line relays 35^b and 33^b and releasing their respective armatures 38^b and 39^b. The effect on train 119^a of the line relay 33^b releasing its armature and breaking the circuit at 53^a will in this instance be as follows: No current from battery 110^a will flow owing to circuit being open at both the contacts 52^a and 53^a, the open contact at 52^a being due to the presence of train 119^b in block 12^b and the open circuit at 53^a being due to the train 119^b being present in block 12^b. However, it is only the presence of train 119^b in block 12^b that actually causes the interruptions of the battery circuit 110^a to cease, for should this current be able to pass over the armature 38^a and through the contact 52^a, its direction would be such as to make the westerly coil 51^a a north pole in a manner hereinbefore described. Therefore, no interruptions would take place in connection with the stationary contact 41^a with the further result that the primary 118^a would induce no current into its secondary, and its corresponding safety device would operate in the manner before described. The same effect will take place on train 119^a in block 12^b due to the presence of train 119^b in block 12^a, as has been described taking place on train 119^a when train 119^b had entered block 12^b. It will be observed that in Fig. 7 the forward portion of train 119^b is represented in block 12^b and the rear portion 119^c of said train in block 12^a. While it will be seen that the rear portion 119^c of the train, through short circuiting the battery 10^a,

caused track relay 14^a to release its armature and open the circuit at 31^a containing the battery 30^a, thereby causing line relay 33^a to release its armature 39^a and open the circuit of easterly coil 50^a at contact 53^a, it will be understood that this will have no further effect than to cause all of the current from battery 110^b to pass over the westerly coil 51^c instead of dividing equally and passing partially over 50^a, and as the direction of this current, as heretofore described, is such that when it passes over coil 51^c said coil is made a south pole, thereby causing vibrations of the north pole armature 45^c, the pulsations in the circuit containing the primary winding 118^b will continue with the effect that the safety device associated with its secondary will not operate to affect the train or engine 119^b.

Fig. 8 illustrates the adaptability of my invention to a siding of a railway track. 9 indicates that portion of the siding which is not blocked, so that a train in such block transmits and receives no signals. Portions 12^x, 12^y of the siding at the extremes of block 9 are electrically continued to block 12. By means of the bonds, 5, 5^a, 5^b, 5^c, 5^d, 5^e, the sections 12^x, 12^y are made continuous of the block 12, in either position of the switches. Track relay 14 is shown in circuit with the block section 12^y and 12^x, and the wires 40 and 55 connect with third rail block 11, this being essentially the same as in the wiring in Fig. 7. With a train in a block adjacent block 12, (Fig. 8) to the right or left thereof, the same effect would be produced in block 12 as has heretofore been described with respect to block 12 in Fig. 7, and if a train is in block 12 or on the portions of the sections 12^x, 12^y, the effect in the blocks to the right or left will be similar to that heretofore described. Numerals 6, 6^a, in Fig. 8, indicate the switch rods, 7 and 7^a the contacts normally open when the switches are closed, and 8, 8^a indicate terminal connections to the rails, and 7, 7^a are adapted to be brought in contact with 8 and 8^a, they being permanently fixed and moving with 6 and 6^a. These parts may be of any well known construction in block signals. While it has been stated that with a train completely in block 9 there will be no effect upon the signals of the system, it will be understood that if a portion of the train is in block 9 and any parts in block 12^x or 12^y, then by reason of the latter portion of the train being in such block the signals will be operated in a manner similar to the operation of such signals if the train were wholly in block 12. Furthermore, if the train were partly in a block section 12^x or 12^y and partly in a block at the right or left thereof, the effect upon the signals will be the same as if the train were partly in block 12 and partly in the block to the right or

left of the latter, in accordance with the previous description, to wit: with respect to train 119^b, 119^c, in blocks 12^c, 12^d.

Fig. 9 illustrates the adaptation of my invention to the crossing of single railway tracks. The blocks 12 of the respective tracks are shown in series by reason of the bonds and the wires 17, 18, so that if an engine or car is in either one of said block sections the line relay 14 will be deenergized, in the manner and for the purpose before described, with respect to all the blocks around the block sections 12 against approach of trains in any direction. For simplicity of illustration I have, in Fig. 9, illustrated merely the parts 33, 53; 33^a, 53^a; 35, 52; and 35^a, 52^a, but it will be understood that the corresponding parts illustrated in previously described figures are to be associated therewith in the manner shown and described hereinbefore. It will be observed, however, that the relays 33, 33^a, 35, and 35^a are in series with the armature of the track relay 14, and that battery 10 is bridged across the rails of blocks 12, 12. The effect of this arrangement is that if battery 10 is short circuited or open circuited, thus permitting relay 14 to drop its armature and open the circuit of battery 30 at 31, the crossing block will be protected through the line relays 33, 33^a, 35, 35^a in the same manner as shown in Fig. 7. The two sections of block 12 are placed in series in order that a train standing on either one will short circuit battery 10 and cause relay 14 to drop its armature. Likewise relays 33, 33^a, 35, 35^a are placed in series in order that when relay 14 is deenergized the third rail blocks 11, 11^b, 11^c, 11^d, which are adjacent to the third rail blocks 11^a, 11^d, may be so affected, as hereinbefore described, that when a train in either of these blocks approaches the crossing the interruptions will cease in the third rail circuit, with the effect heretofore described with reference to Fig. 10, to operate the safety device of the engine.

It has been stated that either positive or negative current may be sent from battery 110, 110^a, etc., to the third-rail, and this in accordance with the direction of travel of an engine with respect to the installation of the system. In Fig. 10 an arrangement is shown more fully in detail whereby shoe 100 when dragging rearwardly on the third rail with respect to the direction of travel of the engine, will cause positive current to be sent over the third-rail, and if the engine should travel in a reverse direction a reverse current will be sent over third-rail. For this purpose I provide a pole changer and circuits described as follows: to the shoe 100 arms 101 are pivotally connected, and are in turn provided with slots 102 receiving supporting pins or the like 103 sustained by the supports 190 on the engine. Arms 101

are connected by bar 104 from which an upright 105 extends, whereby said upright may be adjusted to opposite positions in accordance with the manner in which the shoe drags upon the third-rail. Pole changer 70 arms 107 and 108 are pivotally supported at their lower ends and are operatively connected with upright 105 by a suitable insulating connection 106 whereby arms 107 and 108 may be rocked. In one position, as in Fig. 10, arm 107 will lie upon contact 111 and arm 108 will lie upon contact 112, and when the parts are shifted, say by the engine traveling in a reverse direction, then arm 107 will engage contact 112 and arm 108 will 80 engage contact 111^a. One side of battery 110 is connected with arm 107 and the other side of battery 110 is connected with arm 108. Contacts 111 and 111^a are connected with shoe 100 as by wire 113 and contact 112 is connected by wire 114 with the primary winding 118 of transformer 120. When shoe 100 of engine 119 is dragging, as in Fig. 10, then arms 107 and 108 will respectively engage contacts 111, 112, and the flow of current on the line will be from the positive side of the battery 110, through arm 107 and returning through arm 108, it being understood that these parts form a portion of the circuits of such battery heretofore described. If the shoe drags in a reverse direction to that stated, then the flow of current will be from the positive side of the battery through arm 107 to contact 112, and return through contact 111^a, arm 108 to the negative side of the battery, causing negative current to flow to the third rail. From this it will be seen that since the coils 50, 50^a, etc., 51, 51^a, etc. are adapted respectively to operate with currents of opposite polarity, the arrangement of transmitting current from battery 110, 110^a etc. by means of the position of the shoe relatively to the direction of travel of the engine, will automatically cause the proper current to be sent over the third-rail for operating either of such coils as corresponds thereto to produce the required operation of a safety device in an approaching train without requiring attention from the engineer. In Fig. 10 the part 59 represents a permanent magnet connected with armature 45 for making the latter a permanent north pole armature, but this may be accomplished in any well known manner.

Figs. 11, 12, 13 and 14 represent a practical embodiment of the polarized interrupters heretofore described, showing the parts associated with the coils 50, 51 of the interrupter in producing a practical device 125 for the purpose set forth. The armature 45 (Fig. 14) is shown comprising a frame 56 having magnetized portions 57, 58. By having the springs 42, 44 on opposite sides of armature 45 (Fig. 13) and the stationary 130

5 contact 41 also between said springs, the latter normally engaging contact 41, it will be understood that the circuit 40, 42, 41, 44 and 46 will be broken by the movement of 70 armature 45 in either direction from its normal central position occasioned by the energizing of either coil 50 or 51; provided, of course, that the magnetic attraction of the armature is sufficient at any time to 75 overcome the tendency of spring 42 or 44 to remain in engagement with contact 41. Fig. 12 illustrates in plan the armature pieces 57, 58 between the respective poles of coils 50, 51.

10 15 Fig. 11^a illustrates a modified form of the polarized interrupters illustrated in Figs. 10 to 14, and intended to accomplish the same results as coils 50, 51, etc. In this case the relay 200, 201 and the relay 202, 203 are 80 ordinary polarized relays, and their respective armatures 207, 208 are permanently magnetized as, for instance, north. The relays 200, 201 and 202, 203 are electrically in parallel, their armatures being connected 85 90 95 100 105 110 115 120 125 130 in series with the line, and the action is as follows: consider a positive current as entering wire 40; thence through armature 208, and through contact 205, wire 206, contact 204, armature 207, to junction 209. With both contacts 52 and 53 closed the current will divide equally, one-half passing over coil 202, making it a south pole, and through coil 203 making it a north pole, through contact 53 to junction 54. The effect of this 110 would be to cause the armature 208 to remain more firmly in contact at 205 than the ordinary spring tension would cause. Therefore, the other half of the current proceeding from 209 through 201, making it a south pole, thence through 200 making it a north pole, through contact 52, to junction 54, thence to negative of battery source, through wire 55. As coil 201 is now a south pole it will attract the permanent north pole armature 207, and coil 200 being a north pole will repel the armature 207, therefore the combined pulling and repelling force of these two coils opens the circuit at 204, and the entire circuit will be broken. As the relays are then deenergized the spring will again close the circuit at 204 and the operation will be repeated. It will be seen that the operation is generally the same as that heretofore described with reference to Figs. 10 to 14, and the current reversed by reason of the reversal of the position of shoe 100, and positive current entering through wire 55, and dividing at 54, dividing through the respective relays 200, 201, and 202, 203, reuniting at junction 200, the current will continue to be interrupted, but in this case interruptions will be due to the action of the relay 202, 203 instead of the relay 200, 201, in the following manner: one-half the current passing from 54 through contact 52, and the devices

on the engine illustrated in Fig. 5, and the shoes 100, 100^a, etc., and in addition thereto I provide means controlled by certain of said relays for causing operation of signal 140 when in a block two removed from danger, on either side thereof, and approaching the latter, and the operation of train stopping device 162 when in a block next adjacent to danger on either side thereof and approaching danger. For convenience, in Fig. 15, I have shown battery 30 provided with wires 36 and 37, utilizing such battery for any desired number of blocks instead of utilizing a single battery 30, 30^a, etc., for each block. It will be understood that when a train is in a block, such as train 119^a in block 12^b, the devices represented generally at 14^c, 35^b and 33^a, operate substantially in the same manner as before described, but 20 additional contacts are applied to the armatures of the relays 33, 33^a, etc., 35, 35^b, etc., in order to effect results that will appear in the following description: These additional contacts are shown at 62, 62^a, etc., 67, 67^a, 25 etc., 93, 93^a, etc., 97, 97^a, etc.

In reference to the control of the danger signal 140 (as constituted in Fig. 5), assume that train 119 occupies block 12, and that train 119^a occupies block 12^b, there being an intermediate unoccupied block 12^a. Both trains will receive danger signals due to one train causing cessations of pulsations in the primary coil 118 or 118^a of the other train, and vice versa. Tracing the effect of train 119, it will be seen that battery 10 is short circuited in manner before described, and therefore track relay 14^a will have dropped its armature and opened the circuit at 31^a. The current which normally 40 flowed from the common wire 37, through 31^a and 35^a has thus been broken, and relay 35^a will have dropped its armature, which will cause a break in the circuit of relay 61^b at 62^a. Relay 61^b will now drop its armature by being deenergized, because of the break in its circuit at 62^a. This dropping of the armature of 61^b and making contact at 82^b will divert the path of the current from the engine battery 110^a so that all of 50 such current will pass through coil 50^b and coil 51^b will be cut out. The circuit will be from positive of battery 110^a (of engine 119^a) to shoe 100^a, third-rail 20, wire 40^b to 44^b, 41^b, 42^b, 46^b to point 47^b, thence over wire 48^b, coil 50^b, to point 86^b, thence through contact 82^b, armature of relay 61^b to contact 52^b, armature of relay 35^b, wire 55^b to track, thence through wheels of engine 119^a, primary 118^a (through circuit breaker 115 Fig. 5), thence to negative of battery. It will be seen that no current will now pass through coil 51^b because of the opening of the circuit at 81^b and 83^b, and also because of the position of the armature 60 of relay 33^b which at this time is released

because relay 33^b is deenergized, the latter having been effected when train 119^a was in block 12^c and being maintained deenergized by the train now being in block 12^b, as will be explained hereinafter. These various circuit changes have been effected as follows: Through the establishment of circuit at 82^b and the closed position of the armature of relay 35^b current from battery 110^a has a complete circuit. However, if 75 relay 66^b should drop its armature, due to it becoming deenergized for any reason, it would not permit of the current from battery 110^a dividing at the point 47^b, thus energizing the coil 51^b as the circuit through 80 the armature of 66^b will be found open at contact 53^b, and the position of the armature of 33^b will remain open until train 119^a has passed completely into block 12^a, as will be more fully described hereinafter. When 85 positive current from battery 110^a flowed through the circuit as described, entering the coil 50^b through the wire 48^b, its direction was such as to make the coil 50^b a north pole with the effect that armature 45^b 90 would be repelled and no interruptions in the circuit would occur as before explained. Therefore, because of no pulsations being caused in primary 118^a of the induction coil of train 119^a the safety signal 140, Fig. 5, 95 of such train would operate in the manner before described. Similar results with similar circuits will be caused to effect the safety signal 140 of train 119 by reason of the fact that all the current from battery 100 110 of train 119 was caused to flow through the westerly coil 51 making it a north pole, due to battery 110 sending positive current to track and negative current to third-rail. It will be understood that the devices associated with blocks two removed to the rear of each train 119, 119^a, in conjunction with the devices on engines entering such blocks from the rear, will cause corresponding effects upon the safety signals 140 of such 110 engines when the latter enter such blocks, thereby causing signals in such engines to indicate danger two blocks ahead respectively.

As before referred to, when train 119^a 115 was in block 12^c it affected the circuits in conjunction therewith in the following manner: track battery 10^c having been short circuited by the train, it caused track relay 14^d to become deenergized and drop its armature, opening the corresponding line relay circuit at 31^c. The opening of this circuit causes the relays 35^a, 90^c and 33^b to become deenergized, each dropping its armature. The effect of the relay 33^b dropping its 120 armature, is further utilized when the train enters block 12^b, as it will be understood that regardless of the length of the train 119^a, for a certain period of time, it causes both the track batteries 10^b and 10^c to be 125 130 135 140

come short circuited at the same time, and therefore both the track relays 14^c and 14^a were deenergized at the same time. By following the opened circuit from wire 37 through contact 31^c (which is now open) it will be seen that line relays 35^c, 90^b and 33^a are deenergized, the relays 35^c and 33^a deenergized for the purpose of effecting the same results as has been their function heretofore stated, and the line relay 90^b being deenergized for the purpose of completing a shunt around the relay 33^b, as follows: from point 98^b, thence through the contacts 97^b, the contact 96^b, to point 95^b, and the wire leading therefrom to the point 68^b. Such shunt is utilized for the purpose of keeping the relay 33^b from again becoming energized after train 119^a has passed completely out of block 12^c and has permitted the track battery 10^c to again energize track relay 14^d and close the circuit at 31^a, through which contact the current from wire 37 will now flow through the wire 94^a, relay 35^d, thence through the wire to relay 90^e, thence through the wire to the point 98^b, but instead of flowing through the relay 33^b the current now finds a low resistance shunt around said relay as described before, and said relay 33^b remains deenergized until such time as said shunt is broken at 96^b due to the relay 90^b being again energized.

With trains 119 and 119^a in positions shown in Fig. 15, it having been shown how they affect danger signals in each other, it will now be shown how the train stopping devices of both trains will be caused to operate if either of said trains enters the block next to the other, such as block 12^a. Now in case train 119 should enter into block 12^a thereby short circuiting track battery 10^a and deenergizing track relay 14^b, thus opening the circuit at 31^b containing relays 35^b, 90^a and 33, the armature of relay 35^b will be released and open the circuit of battery 110^a contained on engine 119^a in block 12^b in the following manner: tracing from the negative side of the battery 110^a through the circuit breaker 115 (Fig. 5), primary winding 118^a, to wheels of engine 119^a to track of block 12^b, through wire 55^b, to the armatures of the line relays 33^b and 35^b. It will now be seen that the contact at 52^b being broken by the train 119 as just described, and the contact 53^b being broken by means of the relay 33^b as before described, the circuit is found open at 52^b and 53^b, and therefore no current from the battery 110^a can flow through its normal circuit 55^b, 40^b, including the interrupter coil or coils 50^b, 51^b, with the result that the circuit breaker 115 of engine 119^a becomes deenergized. Thereupon in manner before described, the train controlling device 162 of train 119^a is operated to stop such train. Now, while train

119 is in block 12^a, as before stated, the train stopping device 162 of train 119 will operate to stop such train because train 119^a is in block 12^a by reason of the following: First, while train 119 was in block 12 (as is illustrated in Fig. 15) it caused a partial shunt circuit to be established around line relay 35^a of block 12^a, for use when train 119 enters block 12^a, and also while in block 12 affected the circuit through relay 61^b to control danger signal 140 of train 119^a in block 12^b. The partial shunt so formed around relay 35^a is completed when the train 119 partially enters block 12^a by virtue of short circuiting the battery 10^a and causing track relay 14^b to become deenergized, breaking the circuit at 31^b containing the relays 35^b, 90^a, and 33. The release of the armature of relay 90^a establishes the complete shunt around the relay 35^a by closing the contact 92^a as follows: from point 94^a, to the contacts 93^a and the wire to contacts 92^a (now closed) to point 91^a, and should the circuit be closed at contact 31^a, the circuit around relay 35^a will be as follows: from wire 37 to contact 31^a to point 94^a, through contacts 93^a, through wire and contacts 92^a, to point 91^a, thence through wire to relay 90 etc. The circuit of third rail block 11^a now being open at contact 52^a and the contact 53^a being open due to the presence of train 119^a in block 12^b, causes battery 110 to find no circuit through either of the armatures of the line relays 33 or 35^a. Therefore, the circuit breaker 115 of the train 119 now in block 12^a will be deenergized, causing the operation of the corresponding train stopping devices 162, with the result of stopping train 119. Notwithstanding the presence of trains 119, 119^a in the adjacent blocks 12 and 12^b, with the result of each train causing the other to be stopped in its corresponding block, it will be understood that each train affects the corresponding circuits in the two blocks to its rear, for setting a danger signal or stopping a train in such blocks respectively as before described.

While in Fig. 10 I have illustrated the shoe 100 and a pole changer operated thereby, in conjunction with third rail 20 on one side only of the track, whereby with the engine running in either direction, either ahead or reversely, the pole changer will be shifted accordingly to throw the proper current on the line, in Fig. 16, I have illustrated the track provided with third rails 20 and 20^a on opposite sides, and two shoes 100, 100^a and corresponding pole changers controlled by each shoe, the arrangement being such that if one of the third rails only is adjacent the track for any particular distance, then the proper current will be thrown on the line by the action of the corresponding shoe in conjunction with such third rail. The arrangements shown in Fig. 13

16 for this purpose are as follows: such shoes are one on each side of the engine, and the third rail is placed on either side of the track, or alternately on one side and on the other, and the dragging of the respective shoes is adapted, through their respective pole changers, to always furnish current of a corresponding polarity to the third rail regardless of which shoe is in contact with the third rail 20 or 20^a, the battery 110 being correspondingly connected to the respective pole changers. Therefore, it will be seen that should the engine be turned around the shoes would then assume a direction 15 which would cause an opposite polarity of current to be furnished to the third rail unless the battery 110 was reversed, assuming that the engine proceeded in the same direction in which it was traveling before it was 20 turned around. Such reversal of the battery 110 may be accomplished by operating manually the pole changer B, Fig. 16.

In Fig. 17 the battery 110 is shown so connected to the respective pole changers 25 controlled by shoes 100 and 100^a, that should the engine be turned around and still proceed in a given direction the same polarity of current would be furnished to the third rail provided the third rail always remained 30 on the same side of the track. This is brought about by the battery 110 being oppositely connected to the respective pole changers, looking at the drawing as shown, and the respective shoes are shown in an 35 opposite position, it being understood that should the engine be turned around from a given direction of travel and still continue to proceed in the same direction as before, the shoe 100^a would then engage third rail 40 20 and would be found to assume the same position as shoe 100, as illustrated. Therefore, the same polarity of current would be furnished to the rail 20 as before the engine was turned around. It will, therefore, be 45 seen in respect to the connection shown in Fig. 17, that regardless of the position of the engine with respect to the direction of its travel, positive current will always be furnished the third rail when the engine is 50 moving toward the right, and negative current when the engine is moving toward the left.

Both in respect to Figs. 16 and 17, it is intended that duplicate shoes shall be furnished both sides of the engine, one to be located at one end of the engine proper, the other to be located at the other end of the tender, or in the case of a locomotive having no tender then at the opposite ends of such 60 locomotive. This in order that should it be found necessary to have a bonded gap in the third rail or rails that one of the shoes would remain in contact with a third rail in any well known manner.

65 From the description of the action of the

pole changer set forth with respect to Fig. 10, it will be apparent how the pole changers and their circuits shown in Figs. 16 and 17 will cause positive or negative current, as above described, to be sent over the third rail, according to the direction of travel or position of the engine with respect to such direction of travel, and according to whether one or the other of the shoes dragged upon either third-rail. 75

It will be apparent that with either form of interrupter herein set forth the current strength is decreased, as upon the break in the interrupter circuit caused by the action of the interrupter, hence the current strength 80 may be varied from maximum to any point down to zero, and the term "interrupter" as used herein is intended to embrace all forms of current varying devices, the result of whose operation is to decrease the current 85 in that part of the circuit containing an electrically operating device adapted to be affected only by the periodic variations in the strength of such current, as distinguished from current varying devices which would 90 operate to increase the current strength in such circuit. It will be seen that by decreasing the current strength, as aforesaid, greater variations of such current strength, 95 in that part of the circuit containing the devices to be affected by such variations, may be had, than by increasing the current strength, for by decreasing such current strength its value may be varied from maximum to any point down to zero, such as 100 when the circuit is broken by a magnet overcoming a spring tension which may normally hold the circuit closed, or by such magnet acting upon an armature to short circuit the source of electric energy; while 105 by increasing the current strength in the circuit it is obvious that the minimum current must be above zero in order that such current may be utilized to increase the current strength in that part of the circuit containing 110 the electrically operating means to be affected by the variations or periodic increases in such current. It will further be understood that a current varying device capable of causing great variations in the 115 current strength of a circuit, such as I have disclosed, possesses advantages over a current varying device that is only adapted to cause a lesser variation in such current strength, when the characteristics of a variable or pulsating current is utilized to affect or control an electrically operating device for controlling railway signal or safety devices, since it is obvious that any such device depending for its operation on the 120 periodic variations of the strength of an electric current will be affected proportionately to the variations in the strength of such current. 125

While I have illustrated and described a 130

practical embodiment of my invention, and means for carrying the same into effect, it will be understood that my invention is not limited to the particular arrangements set forth, but changes may be made, within the scope of the appended claims, without departing from the spirit of the invention.

Having now described my invention what I claim is:

- 10 1. In a railway block system, a track and third-rail divided into corresponding blocks, a partially closed circuit associated with the track and third-rail of a block, an interrupter in said circuit, and electrically operating means associated with another block for controlling the circuit of said interrupter.
- 15 2. In a railway block system, a track and third-rail divided into corresponding blocks, a partially closed circuit associated with the track and third rail of a block, an interrupter in said circuit, a relay to control the circuit of said interrupter, and a circuit for said relay associated with a block different from the block of said interrupter.
- 20 3. In a railway block system, a track and third rail divided into corresponding blocks, a partially-closed circuit associated with the track and third-rail of a block, an interrupter in said circuit, a relay to control the circuit of said interrupter, and a circuit for said relay associated with the rails of a block different from the block of said interrupter, and a battery bridged across said
- 25 4. In a railway block system, a track divided into blocks, a partially closed circuit associated with each block and containing means for producing current pulsations in the circuit, electrically operating means associated with another block for controlling said circuit, a safety device, electrically operating means operative by pulsating current to control said safety device, and means for completing said circuit through said electrically operating means.
- 30 5. In a railway block system, a track divided into blocks, a partially-closed circuit associated with each block and containing means for producing pulsations in the circuit, electrically operating means associated with another block for controlling said circuit, an induction coil, means for completing the circuit of the primary of said induction coil through the first named circuit, a safety device, and means controlled by the secondary of said induction coil for controlling said safety device.
- 35 6. In a railway block system, a track divided into blocks, a partially-closed circuit associated with each block, and containing means for producing current pulsations in the circuit, electrically operating means associated with another block for controlling said circuit, an induction coil, means for completing the circuit of the primary of said induction coil through the first named circuit, a safety device, means controlled by the secondary of the induction coil for controlling the safety device.

completing the circuit of the primary of said induction coil through the first named circuit, a circuit controller in the circuit of the secondary of the induction coil, a safety device, and electrically operating means for the safety device having its circuit controlled by said circuit controller.

7. In a railway block system, a track divided into blocks, a partially closed circuit associated with each block and containing means for producing current pulsations in the circuit, electrically operating means associated with another block for controlling said circuit, an induction coil, means for completing the circuit of the primary of said induction coil through the first named circuit, a circuit controller in the circuit of the secondary of the induction coil, a safety device, electrically operating means for controlling the safety device, and a local circuit for said means controlled by said circuit controller.

8. In a railway block system, a track divided into blocks, a partially-closed circuit associated with each block and containing means for producing current pulsations in the circuit, electrically operating means associated with another block for controlling said circuit, an induction coil, means for completing the circuit of the primary of said induction coil through the first named circuit, a safety device, means controlled by the secondary of the induction coil for controlling the safety device, a second safety device, and means included in the circuit of the primary of the induction coil for controlling the last named safety device.

9. In a railway block system, a track divided into blocks, a partially-closed circuit associated with each block and containing means for producing current pulsations in the circuit, electrically operating means associated with another block for controlling said circuit, an induction coil, means for completing the circuit of the primary of said induction coil through the first named circuit, a safety device, means controlled by the secondary of the induction coil for controlling the safety device, a second safety device, a circuit controller in the circuit of the primary of the induction coil, and means controlled by said circuit controller for controlling the second safety device.

10. In a railway block system, a track divided into blocks, a partially-closed circuit associated with each block and containing means for producing current pulsations in the circuit, electrically operating means associated with another block for controlling said circuit, an induction coil, means for completing the circuit of the primary of said induction coil through the first named circuit, a safety device, means controlled by the secondary of the induction coil for controlling the safety device.

device, a second safety device, a circuit controller in the circuit of the primary of the induction coil, electrically operating means for controlling the second safety device, and 5 a local circuit for said means controlled by the circuit controller.

11. In a railway block system, a track divided into blocks, a partially closed circuit associated with each block and containing means for producing current pulsations in the circuit, electrically operating means associated with another block for controlling said circuit, a safety device, electrically operating means to control said 15 safety device, and means for completing the circuit of said electrically operating means through the first named circuit, said means comprising a shoe, and a pole changer operated by said shoe, said pole changer 20 having a contact in said circuit.

12. In a railway block system, a track divided into blocks, a partially closed circuit associated with each block and containing means for producing current pulsations in the circuit, electrically operating means associated with another block for controlling said circuit, a safety device, electrically operating means to control said safety device, and means for completing the 25 circuit of said electrically operating means through the first named circuit, said means comprising a shoe, and a pole changer operated by said shoe, said pole changer having a contact 112 in said circuit, and having 30 a plurality of movable contacts 107 and 108.

13. In a railway block system, a track divided into blocks, a partially closed circuit associated with each block and containing means for producing current pulsations in the circuit, electrically operating means associated with another block for controlling said circuit, a safety device, electrically operating means to control said safety device, and means for completing 45 the circuit of said electrically operating means through the first named circuit, said means comprising a shoe, and a pole changer operated by said shoe, said pole changer having a contact in said circuit, and 50 having a plurality of movable contacts 107 and 108, and a battery having its terminals connected with the arms of the pole changer.

14. In a railway-block system, a track divided into blocks, a partially-closed circuit associated with each block and containing means for producing current pulsations in the circuit, electrically operating means associated with another block for controlling said circuit, an induction coil, means for 55 completing the circuit of the primary of said induction coil through the first named circuit, said means comprising a shoe, and a pole changer operated by said shoe, said pole changer having a contact connected 60 with the primary of said induction coil and

having a plurality of contacts connected with the shoe.

15. In a railway-block system, a track divided into blocks, a partially-closed circuit associated with each block and containing 70 means for producing current pulsations in the circuit, electrically operating means associated with another block for controlling the said circuit, an induction coil, means for completing the circuit of the primary 75 of said induction coil through the first named circuit, said means comprising a shoe and a pole changer operated by said shoe, said pole changer having a contact connected with the primary of said induction 80 coil and having a plurality of contacts connected with the shoe, and a battery connected with the arms of the pole changer.

16. In a railway block system, a track divided into blocks, an engine adapted to 85 travel on said track, a safety device on the engine, an induction coil on the engine, electrically operating means controlled by the secondary of the induction coil for controlling said safety device, a second safety 90 device on the engine, electrically operating means controlled through the primary of said induction coil for controlling said second safety device, partial circuits and electrically operating devices to control the same 95 associated with said track blocks, and means for completing said partial circuits through the primary of the induction coil.

17. In a railway block system, a track divided into blocks, an engine adapted to 100 travel on said track, a safety device on the engine, an induction coil on the engine, electrically operating means controlled by the secondary of the induction coil for controlling said safety device, partial circuits and 105 electrically operating devices to control the same associated with said track blocks, and means for completing said partial circuits through the primary of the induction coil, said means including an electric generator 110 carried by the engine.

18. In a railway block system, a track divided into blocks, an engine adapted to travel on said track, a safety device on the engine, an induction coil on the engine, electrically operating means controlled by the secondary of the induction coil for controlling 115 said safety device, a second safety device on the engine, electrically operating means included in the circuit of the primary 120 of said induction coil for controlling said second safety device, partial circuits and electrically operating devices to control the same associated with said track blocks, and means for completing said partial circuits 125 through the primary of the induction coil, said means including an electric generator carried by the engine.

19. In a railway block system, a track divided into blocks, an engine adapted to 130

- travel on said track, a safety device carried by the engine, electrically operating means for controlling said safety device comprising an electric generator normally energizing such device, an induction coil on the engine, electrically operating devices controlled by the secondary of said induction coil to control said electrically operating means, partial circuits and electrically operating devices to control the same associated with the blocks, and means for completing a partial circuit through the primary of said induction coil, whereby when the circuit of said primary of the induction coil is retained opened said safety device will be operated.
20. In a railway block system, a track divided into blocks, a partially closed circuit associated with each block and containing means for producing current pulsations in each circuit, and electrically operating means associated with one block for controlling such circuits in two blocks.
21. In a railway block system, a track divided into blocks, a partially closed circuit associated with each block and containing means for producing current pulsations in each circuit, and electrically operating means associated with one block for stopping pulsations in the said circuit of another block and causing direct current in such circuit and a safety controlling device in said circuit operative by direct or interrupted current.
22. In a railway block system, a track divided into blocks, a partially closed circuit associated with each block and containing means for producing current pulsations in each circuit, and electrically operating means associated with one block for breaking such circuit in another block and for stopping pulsations in the said circuit of a further block and causing direct current in the last named circuit, and a safety controlling device in said last named circuit operative by direct or interrupted current.
23. In a railway block system, a track divided into blocks, a partially closed circuit associated with each block and containing means for producing current pulsations in the circuit, a relay for controlling such circuit, electrically operating means controlled by the relay associated with one block for cutting out the means for producing pulsations in the circuit of an adjacent block, and for preventing pulsations in the circuit of another block and causing direct current to flow through such circuit.
24. In a railway block system, a track divided into blocks, a partially closed circuit associated with each block and containing an interrupter, a relay associated with one block to control the circuit of the interrupter of a second block, and means con-

trolled by said relay to control the circuit 65 of the interrupter of a third block.

25. In a railway block system, a track divided into blocks, a partially closed circuit associated with each block and containing an interrupter, a track relay in circuit 70 with each of the track blocks, two line relays for controlling the interrupter circuit of each track block, and means for controlling a line relay of two blocks by the track relay of an intermediate block.

26. In a railway block system, a track divided into blocks, a partially closed circuit associated with each block and containing an interrupter, a track relay in circuit with each of the track blocks, two line relays for 80 controlling the interrupter circuit of each track block, line relays of two blocks on opposite sides of a track relay having a common circuit controlled by such track relay, whereby the interrupter circuits of two 85 blocks on opposite sides of such track relay are simultaneously controlled.

27. In a railway block system, a track and third rail divided into corresponding blocks, a partially closed circuit associated 90 with the track and third rail of a block, a track relay in circuit with each of the track blocks, two line relays for each first named circuit having armatures for controlling the corresponding first named circuit, line relays of two blocks on opposite sides of a track relay having a common circuit controlled by such track relay, whereby the first named circuits of the two blocks are 95 simultaneously controlled.

28. In a railway block system, a track and third rail divided into corresponding blocks, a partially closed circuit associated with the track and third rail of a block, a track relay in circuit with each of the track 105 blocks, two line relays for each first named circuit having armatures for controlling the corresponding first named circuit, and means for controlling a line relay of two blocks by the track relay of an intermediate 110 block.

29. In a railway block system, a track and third rail divided into corresponding blocks, a partially closed circuit associated with the track and third rail of a block, said circuit having two branches in multiple, line relays for each block to control said branches respectively, a track relay for each block, and means for controlling the line relays by said track relays.

30. In a railway block system, a track and third rail divided into corresponding blocks, a partially closed circuit associated with the track and third rail of a block, said circuit having two branches in multiple, line relays for each block to control said branches respectively, a track relay for each block, and means for causing the track 125

relay of one block to control a line relay of two other blocks.

31. In a railway block system, a track and third rail divided into corresponding blocks, a partially closed circuit associated with the track and third rail of a block, said circuit having two branches in multiple, line relays for each block to control said branches respectively, a track relay for each block, line relays of two blocks having a common circuit controlled by the track relay of an intermediate block.

32. In a railway block system, a track and third rail divided into corresponding blocks, a partially closed circuit associated with the track and third rail of a block, said circuit having two branches in multiple, an interrupter coil in each such branch, means controlled by said coils to make and break said first named circuit, line relays for each block to control said branches respectively, a track relay for each block, and means for controlling the line relays by said track relays.

33. In a railway block system, a track and third rail divided into corresponding blocks, a partially closed circuit associated with the track and third rail of a block, said circuit having two branches in multiple, an interrupter coil in each such branch, means controlled by said coils to make and break said first named circuit, line relays for each block to control said branches respectively, a track relay for each block, and means for causing the track relay of one block to control a line relay of two other blocks.

34. In a railway block system, a track and third rail divided into corresponding blocks, a partially closed circuit associated with the track and third rail of a block, said circuit having two branches in multiple, an interrupter coil in each such branch, means controlled by said coils to make and break said first named circuit, line relays for each block to control said branches respectively, a track relay for each block, line relays of two blocks having a common circuit controlled by the track relay of an intermediate block.

35. In a railway block system, a track and third rail divided into corresponding blocks, a partially closed circuit associated with the track and third rail of a block, said circuit having two branches in multiple, line relays for each block to control said branches respectively, a track relay for each block, and means for controlling the line relays by said track relays, and means to shunt a line relay in a block and maintain open the branch of the first named circuit previously opened by said line relay.

36. In a railway block system, a track and third rail divided into corresponding blocks, a partially closed circuit associated with the

track and third rail of a block, said circuit having two branches in multiple, an interrupter coil in each such branch, means controlled by said coils to make and break said first named circuit, line relays for each block to control said branches respectively, a track relay for each block, and means for controlling the line relays by said track relays.

37. In a railway block system, a track and third rail divided into corresponding blocks, a partially closed circuit associated with the track and third rail of a block, said circuit having two branches in multiple, an interrupter coil in each such branch, means controlled by said coils to make and break said first named circuit, line relays for each block to control said branches respectively, a track relay for each block, means for controlling the line relays by said track relays, and means controlled by line relays for directing the flow of current through one or the other of said interrupter coils.

38. In a railway block system, a track and third rail divided into corresponding blocks, a partially closed circuit associated with the track and third rail of a block, said circuit having two branches in multiple, an interrupter coil in each such branch, means controlled by said coils to make and break said first named circuit, line relays for each block to control said branches respectively, a track relay for each block, and means for controlling the line relays by said track relays, relays 61, 66 controlled by the line relays to control the flow of current through one or the other of said coils.

39. A railway safety system comprising a safety device, electrically operating means therefor, an induction coil having one of its coils in circuit with said means, an electric generator for the circuit of one of the coils of said induction coil, a pole changer having contacts for the circuit of said generator, and a shoe connected with the pole changer for operating the latter to cause positive or negative current from said generator to flow through the last named coil of the induction coil.

40. A railway safety system comprising a safety device, electrically operating means therefor, an induction coil having one of its coils in circuit with said means, an electric generator for the circuit of one of the coils of said induction coil, a plurality of pole changers each having contacts for the circuit of said generator, and a shoe connected with each pole changer.

41. A railway safety system comprising a plurality of safety devices, electrically operating means for each safety device, an induction coil having one of its coils in circuit with one of said electrically operating means, and its other coil in circuit with the other of said electrically operating means, an electric generator for the circuit of one

- of the coils of said induction coil, a pole changer having contacts for the circuit of said generator, and a shoe connected with the pole changer for operating the latter to cause positive or negative current from said generator to flow through the last named coil of the induction coil.
42. A railway safety system comprising a plurality of safety devices, electrically operating means for each safety device, an induction coil having one of its coils in circuit with one of said electrically operating means, and its other coil in circuit with the other of said electrically operating means, an electric generator for the circuit of one of the coils of said induction coil, a plurality of pole changers having contacts for the circuit of said generator, and a shoe connected with each pole changer.
43. A safety system comprising a plurality of safety devices, an induction coil, a circuit controller in the circuit of one coil of the induction coil, electrically operating means controlled by said circuit controller for controlling one of said safety devices, a circuit controller in the circuit of another of the coils of the induction coil, electrically operating means controlled by the last named circuit controller for controlling the other of said safety devices, an electric generator for the circuit of one of the coils of the induction coil, a pole changer having contacts for the circuit of said generator, and a shoe connected with the pole changer for operating the latter to cause positive or negative current from said generator to flow through the last named coil of the induction coil.
44. In a railway safety system the combination of an engine, a safety device carried by the engine biased to danger position, electrically operating devices governing said safety device, and electrically operating means controlled by interrupted current for controlling said electrically operating devices for normally retaining said safety device at safety, whereby when the interruptions of said current cease the safety device will go to danger.
45. In a railway safety system, a circuit, a safety device, means to change the controlling current from interrupted to direct continuous current, and means controlled by interrupted current for retaining said device at safety and for releasing said device when the said interrupted current is changed to direct continuous current.
46. In a railway safety system, a circuit, a safety device, electrically operating means for producing interruptions in the circuit and also for retaining said device at safety and for releasing said device when the interruptions cease, a second safety device and electrically operating means for retaining said second safety device at safety and for releasing said device when current flow ceases, said second named means being controlled by interrupted or direct current.
47. In a railway safety system the combination of a safety device, an induction coil, electrically operating means controlled by the secondary of said induction coil for retaining said device at safety when the coil is energized, means for energizing said coil, a second safety device, and electrically operating means to control said second safety device, said means being controlled by either interrupted or direct current in the circuit of the primary of said induction coil.
48. In a railway safety system the combination of a safety device, an induction coil, electrically operating means controlled by the secondary of said induction coil for retaining said device at safety when the coil is energized, means for energizing said coil, a second safety device, and electrically operating means therefor operative to retain the second named safety device at safety by either direct or interrupted current in the circuit of the primary of the induction coil.
49. In a railway block system, a track divided into blocks, a partially closed circuit associated with each block and each of said circuits containing means for producing current pulsations therein, and electrically operating means associated with each block for breaking such partially closed circuit in another block and for stopping pulsations in a partially closed circuit of a further block and causing direct continuous current to flow in the last named circuit, an engine, a safety controlling device on the engine adapted to be included in the partially closed circuit, said controlling device being operative by interrupted current, a second safety controlling device on the engine, and means adapted to be included in the partially closed circuit to control the latter operative by either interrupted or direct current.
- Signed at New York city, in the county of New York, and State of New York this 3rd day of February, A. D. 1912.
